BOAT CRADLE

John S. Howard, Jr., Baltimore, and William P. O. Clarke, Annapolis, Md.; said Clarke assignor to said John S. Howard, Jr.

Application September 24, 1948, Serial No. 50,906

7 Claims. (Cl. 214—1)

1

This invention relates to boat cradles, and is useful when mounted on skids or on a marine railway, but is particularly advantageous when carried upon an automobile trailer.

The primary object of the invention is to provide a cradle which will allow a boat to be rotated whereby the hull may be readily cleaned, scraped, repaired and painted.

Another object of the invention is to provide a structure which upon rotation of the cradle will afford ready and unrestricted access to the entire hull.

An additional feature of the invention is to provide a cradle which will support the boat in a position where it can be worked upon by a standing workman.

A further object of this invention is to provide a cradle construction which, in either of its rotated positions, will support the boat against movement while being worked upon.

The importance of the aforesaid advantages will be appreciated when it is realized that small sailboat racers, for example, are very particular concerning the lightness of their boats, and the condition of the boat bottom. Many keep their boats on trailers between races instead of in the water in order that the hull will not become heavy from water absorbed by the wood. The boats are transported on trailers behind an automobile from one location to another, and in this connection it is very awkward to careen or turn over the boats on these trailers to clean the bottoms. When it is considered that sometimes the boats are turned over for cleaning as often as four times a week, the value of the present invention will be appreciated since it is possible, with this invention, to rotate a boat for treatment of its hull and return it to normal carrying position on a trailer, skid, or marine railway in about two minutes.

Referring to the drawings wherein we have shown the invention for purposes of illustration, mounted upon a trailer:

Figure 1 is a side elevation;

Figure 2 is an end elevation;

Figure 3 is an end elevation showing the cradle rotated to the right and indicating that unrestricted access is made available for operating upon the hull;

Figure 4 is a section on the line 4—4 of Figure 2;

Figure 5 is a section on the line 5—5 of Figure 4;

Figure 6 is an enlarged broken-away side elevation of the boat cradle mount structure for a boat hull;

2

Figure 7 is a section on the line 7—7 of Figure 6; and,

Figure 8 is a section on the line 8—8 of Figure 6.

Referring to Figure 1, we have illustrated the boat at 10, which is mounted upon a cradle indicated as a whole at 11, which, in turn, is carried upon a conventional type of automobile trailer indicated as a whole at 12. Mounted upon the axle of the trailer, as indicated at 13 in Figure 2, is a rectangular frame 14 formed of angle iron members suitably bolted or welded together. Each of the end cross members 14 of this frame has secured at its ends upstanding angle iron supports 15, as best shown in Figure 2. The upper end edges of the supports 15 are inclined inwardly, as shown at 16 in Figure 6, and the intermediate portions of the angle iron are recessed as shown at 17 in Figure 6, and particularly in Figure 1. Referring again to Figure 6, a suitable roller 18 is mounted for free rotation in the sides 19 of each angle iron support 15 upon a shaft 20 for a purpose which will later be described.

The cradle 11 is preferably made of metal such as strap iron but may be made of wood. This cradle is arcuate or semi-circular as shown, and intermediate its ends, has connected to it an upstanding angle iron bar 22. This bar may be connected at its base to the arcuate cradle 11 in any suitable manner, as by bolts, but is preferably welded, as shown at 23 in Figure 3, the bar having a bracket 24 which is welded to the cradle. At its upper end the bar 22 has welded to it a horizontal angle iron bracket 25, as best shown in Figure 6, which extends on either side of the said bar. Mounted on the end cross members 14 intermediate their ends is a housing 26, best shown in Figures 3, 4 and 5. Referring to Figure 4, it will be noted that the angle iron member 14 is disposed within the housing 26, and a roller 27 having trunnions 28 is mounted for free rotation in the walls of the housing and the adjacent wall of the angle iron cross member 14.

Referring to Figure 3, it will be noted that the cradle is supported upon the rollers 18 and 27 for rotation upon the frame 14. This is accomplished by means of the bolts 29, best shown in Figure 2. When the bolts are in locking position for carrying the boat on the trailer, as shown, they hold the cradle against rotation. However, when it is desired to rotate the cradle, these bolts are disconnected and the cradle rotated as shown in Figure 3.

It is preferable to unite the cradles 11 by means of longitudinally extending angle iron members

30, as shown in Figures 1 and 3 to provide a rigid structure.

Referring to Figure 6 particularly, and also to Figures 2 and 3, the boat cradle mount consists of aligned bars 31 which are preferably of wood, and have their opposite inner ends bolted, as shown at 32, to the angle iron 25. Referring to Figures 2, 3 and 6, it will be observed that the keel K of the boat will be disposed and retained in the space 21 between the adjacent opposite inner ends of the independent bars 31 at each end of the frame. A pair of bars 31 is carried on the rotating cradle 11 at each end of the frame. At their outer ends the bars are bolted to the angle irons 34, as shown at 35, the angle irons being 15 suitably welded to the cradle 11. Positioned above the bars 31 are side supports 36 detachably secured to the rotating cradle by means of screws 37 having their heads flush with the outer surface of the cradle members 11. It will be noted that the bars 31, as well as the supports 36, are covered with cloth 38, or any suitable material which will not abrade the surface of the hull, and which will form a cushioned support for the same. The side supports 36 act as wedges and exert a light pressure upon the hull of the boat to hold the same in position. While we have shown the screws 37 as introduced from the outside, as shown in Figure 6, they may be inserted from the inside with their ends terminating short of or flush with the outer surface of the cradle members 11.

Referring to Figure 3 and also to Figure 6, when it is desired to treat one side of the hull, for instance, the left-hand side in Figure 3, the bolts 29 are removed and the cradle 11 is rotated to the position shown. Thereupon the bolts 32 and 35 are loosened with respect to slots 39 formed in the upper plate 40 of angle iron bracket member 25 and in the upper plates 41 of angle irons 34 by loosening the nuts 42, whereby the bar 31 is easily displaced. Also, the side support 36 may, if desired, be detached by removing the screws 37, whereupon complete access may be had to the left side of the hull of the boat, as shown in Figure 3. It is to be understood, of course, that the support 36 and bar 31 on the left-hand side of Figure 3 at each end of the cradle are removed for the treatment of that side of the boat. When one side has been finished, the bar 31 and cushion 36 are replaced, and then the cradle 11 is rotated in the opposite direction from that shown in Figure 3 so that full access may be had to the right-hand or opposite side of the boat. The support 36 and bar 31 on such opposite side of the cradle are then similarly removed for this purpose. When the scraping, cleaning and painting of the hull has been completed, the cradle 11 is rotated to the position shown in Figure 2, and the bolts 29 are mounted so as to connect the cradles 11 to the frame 14 and hold the cradles and the boat in a horizontal position against rotation. The actual operation of removing the bolts 29, and the boat cradle mount structure, namely bars 31 and supports 36, to treat both sides of the hull and return the hull to the normal position shown in Figure 2 occupies about two minutes.

The outer surfaces of the cradle members are unobstructed whereby the boat may be tilted to a position for complete exposure of the hull and adjacent side, the amount of such tilting being limited by the stops 50 at either end of the cradle members engaging the upper ends of the supports 15.

Each cradle member has an opening 51 at

ranged on opposite sides of the support 22, as shown in Figures 2 and 3. When tilted, one of such openings is registered with the bolt openings in the frame member 14 and a bolt 29 inserted to hold the cradle detachably fixed in its tilted position.

Referring to Figure 3 wherein one side of the boat, namely the left side, has been raised, it will be noted that the weight of the boat will balance it so that the boat will remain in the position shown with its center of gravity just inside of the right-hand support 15 and its roller 18. In other words, the boat will remain in the position shown in Figure 3, resting upon the opposite bar 31 and side support 36 at each end of the cradle. In its raised position, the left side of the boat may be readily worked upon by a standing workman.

Referring to Figures 3 and 6, reinforcing rods or braces 43 are provided which are connected to the brackets 25 at their inner ends by bolts 44 and at their outer ends are rigidly bolted to the angle irons 34, as shown at 45. This is to make a rigid support to prevent spreading of the sides 25 of the cradle.

The present invention has been demonstrated to solve many of the problems connected with the transportation, repair and preservation of boat hulls in a highly expeditious manner. For instance, the trailer can be carried far enough into the water so that the boat will readily float off of the mount. Also, the side supports 36 guide the boat to proper position on the trailer when positioning the boat thereon while the latter is in the water. The easy access to all parts of the bottom and hull of the boat, and the fact that there is unrestricted access, due to the rotatable cradle 11 and detachable boat cradle mount structure 31-36, makes the invention not only useful in association with trailers, but generally in boat yards, for instance, where it is now the practice to place small boats on carpenters' horses for repair and painting. It will be noted that when the bolts 29 are removed, the cradle is released for rotation and is held in proper position for rotation at all times by the guiding means provided by the recesses 17. Also, it will be observed that the rectangular frame 14 is readily carried by a trailer or other suitable conveying means and may be detached therefrom where necessary. In removing the members 31-36 of the boat cradle mount, it is preferable to first remove the side supports or cushion wedges 36 which are in superposed relation to the bars 31, but, of course, there are cases where it is desirable to only remove one or the other of such members, and, therefore, the order of their removal is not important.

We claim:

1. A boat cradle comprising a frame, an arcuate cradle member mounted for rotation on said frame, a detachable boat cradle mount carried by said cradle and extending chordally of the cradle, said mount including a plurality of side supports and bottom bars respectively, detachably mounted to said cradle whereby selected ones of said side supports and bars may be removed for permitting unrestricted access to a pre-selected portion of the hull of a boat carried in said mount.

2. A boat cradle comprising a frame, a pair of supports carried by the frame, said supports having rollers at their upper ends, a roller mounted on the frame intermediate said supports, an arcuate cradle member mounted for rotation on said rollers, means for holding said cradle member against rotation and for releasing the same for

rotation, and a detachable boat cradle mount carried by said cradle and extending chordally of the cradle, said mount including a plurality of side supports and bottom bars respectively, detachably mounted to said cradle whereby selected ones of said side supports and bars may be removed for permitting unrestricted access to a preselected portion of the hull of a boat carried in said mount.

3. A boat cradle according to claim 2 wherein said first mentioned supports at their upper ends are provided with guiding means for said cradle member.

4. A boat cradle comprising a frame a cradle member mounted for rotation on said frame, a detachable boat cradle mount carried by said cradle, said mount comprising oppositely disposed aligned bars, each having their inner and outer ends detachably connected to the cradle, and side supports in superposed relation to said bars and detachably connected to said cradle member whereby one of said bars and the adjacent side support may be removed for permitting unrestricted access to a side of the hull of a boat carried in said mount.

5. A boat cradle according to claim 4 wherein the inner ends of the bars of said mount are connected to an upstanding bar which is connected to the cradle intermediate the ends thereof.

6. A boat cradle according to claim 4 wherein there is provided a pair of supports carried by the

frame, said supports having rollers at their upper ends, a roller mounted on the frame intermediate said supports, the cradle member being mounted for rotation on said rollers, means for holding said cradle member against rotation and for releasing the same for rotation.

7. A boat cradle comprising a frame, an arcuate cradle member mounted for rotation on said frame, a detachable boat cradle mount carried by said cradle and extending chordally thereof, said mount including a plurality of side supports and bottom bars respectively, detachably mounted to said cradle whereby selected ones of said side supports and bars may be removed for permitting unrestricted access to a preselected portion of the hull of a boat carried in said mount and a conveying means, said frame being mounted on said conveying means.

JOHN S. HOWARD, JR.
